CLAIM

I claim the ornamental design for a game feeder, as shown and described.

DESCRIPTION

FIG. 1 is a perspective view of a game feeder;
FIG. 2 is a front view of the game feeder of FIG. 1;
FIG. 3 is a rear view of the game feeder of FIG. 1;
FIG. 4 is a left side view of the game feeder of FIG. 1;
FIG. 5 is a right side view of the game feeder of FIG. 1;
FIG. 6 is top view of the game feeder of FIG. 1;
FIG. 7 is a bottom view of the game feeder of FIG. 1; and,
FIG. 8 is an environmental view of the game feeder of FIG. 1.
Broken lines and portions contained within are not claimed.
